US0D1079727S

(12) **United States Design Patent** (10) Patent No.: **US D1,079,727 S**
Kabasser et al. (45) Date of Patent: ** Jun. 17, 2025

(54) **DISPLAY SCREEN OR PORTION THEREOF WITH ICON**

(71) Applicant: **Ivoclar Vivadent AG**, Schaan (LI)

(72) Inventors: **Lukas Kabasser**, Dornbirn (AT);
Tobias Hauptmann, Vienna (AT)

(73) Assignee: **Ivoclar Vivadent AG**, Schaan (LI)

(**) Term: **15 Years**

(21) Appl. No.: **29/911,376**

(22) Filed: **Sep. 1, 2023**

(30) **Foreign Application Priority Data**

Mar. 9, 2023 (EM) 015013968-0005

(51) **LOC (15) Cl.** **14-04**

(57) **CLAIM**

The ornamental design for a display screen or portion thereof with icon, as shown and described.

DESCRIPTION

The sole FIGURE is a front view of a display screen or portion thereof with icon.

The broken lines in the FIGURE show a display screen or portion thereof, and form no part of the claimed design.

1 Claim, 1 Drawing Sheet
